Primary Examiner — Holly Baynham*Assistant Examiner* — Rashida C Walshon(74) *Attorney, Agent, or Firm* — Banner & Witcoff, Ltd.(57) **CLAIM**

The ornamental design for a shoe upper, as shown and described.

DESCRIPTION

FIG. 1 is a front perspective view of a shoe upper showing my new design;

FIG. 2 is a side view thereof; and,

FIG. 3 is a rear perspective view thereof.

The broken lines immediately adjacent to the shaded area in FIGS. 1-3 represent unclaimed boundaries of the design. The broken ones showing the remainder of the shoe in FIGS. 1-3 are for environmental purposes only and form no part of the claimed design.
